[57] CLAIM

The ornamental design for a shelf or similar article, as
shown and described.

DESCRIPTION

FIG. 1 is a perspective view of a shelf or similar article,
showing my new design;FIG. 2 is an enlarged fragmentary view of the shelf or
similar article taken from the left side;FIG. 3 is an enlarged fragmentary view of the shelf or
similar article taken from the front left;

FIG. 4 is a top plan view;

FIG. 5 is a front elevational view;

FIG. 6 is a rear elevational view;

FIG. 7 is a right side elevational view, the left side being

a mirror image thereof;

FIG. 8 is a bottom plan view;

FIG. 9 is a perspective view of a shelf or similar article,
showing an alternate embodiment of my new design;

FIG. 10 is a top plan view of the alternate embodiment;

FIG. 11 is a front elevational view of the alternate em-
bodiment;FIG. 12 is a rear elevational view of the alternate em-
bodiment;FIG. 13 is a left side elevational view of the second
embodiment, the right side being a mirror image
thereof; and,FIG. 14 is a bottom plan view of the alternate embodi-
ment.

The drawing is shaded for color contrast.
